UNITED STATES PATENT OFFICE.

JOHN S. BUTCHER, OF VINELAND, NEW JERSEY, ASSIGNOR OF ONE-HALF TO EDMUND F. SOMERS, OF ROSENHAYN, NEW JERSEY.

RAILROAD-TIE.

980,758.

Specification of Letters Patent.

Patented Jan. 3, 1911.

Application filed May 13, 1910. Serial No. 561,150.

To all whom it may concern:

Be it known that I, JOHN S. BUTCHER, a citizen of the United States, residing at Vineland, in the county of Cumberland and 5 State of New Jersey, have invented new and useful Improvements in Railroad-Ties, of which the following is a specification.

This invention relates to improvements in rail ties, and the object of the invention is 10 to provide a simple and effective device for preventing the spreading of the rails.

The invention resides in the novel construction and combination of elements hereinafter fully described and claimed.

15 In the accompanying drawings, Figure 1 is a perspective view of a pair of rails provided with the improved tie or anti-spread- 20 ing device. Fig. 2 is a detail perspective view of one of the ends of the device with the rails removed. Fig. 3 is a horizontal 25 sectional view through one end of the device. Fig. 4 is a transverse sectional view of the same. Fig. 5 is a detail perspective view of one of the clamping jaws removed 30 from the tie. Fig. 6 is a similar view of the tie.

In the accompanying drawings the numerals 1 designate a pair of rails. Each of the rails 1 is of the ordinary construction, com- 35 prising a head 2, a base flange 3 and a connecting web 4.

The numeral 5 designates the improved tie. This tie 5 is constructed of some suitable metal and comprises substantially a 35 rectangular member. The tie 5 is centrally provided with a longitudinal integrally formed enlargement 7 and the said enlargement has its opposite longitudinally extending edges undercut toward the center of the 40 tie as designated by the numeral 8. The enlargement 7 is so formed that its central portion is reduced and its edges 8 extend at opposite angles toward the ends of the tie, so that the outer extremities of the enlarge- 45 ment are of greater widths than the center of the tie, whereby the inner clamping members, hereinafter to be described, may be slid free of the rails and removed from the tie without the necessity of disconnect- 50 ing said members.

The numeral 9 designates the clamping elements for each of the rails. These elements 55 9 are of a similar construction and the reference characters applied to the se- curing element upon one of the rails and tie

may be taken as equally applicable to the opposite rail and the opposite end of the tie. The member 9 has its base portion horizontally straight to correspond with the flattened face of the tie 5 adjacent the off- 60 set or enlargement 7. The clamp comprises a plurality of members, preferably four in number, and each of these members has its base provided with a substantially V-shaped tongue, which is adapted to engage the inclined side wall 8 of the member 7. Each of the members comprising the clamp has an overlying jaw 11 and positioned directly below the said jaw is a horizontally straight bearing surface 12, the latter being adapted 70 for the reception of the base flange of the rail, while the overlying jaw is adapted to contact and engage the upper face of the said rail. It will be noted by reference to Figs. 1 and 2 of the drawings that a pair of 75 the said clamping elements are arranged adjacent each of the sides of the rail and the body portion of each of the members comprising the tie is provided with longitudinal openings 13 as well as transverse open- 80 ings 14, and the said openings are adapted to align when the members comprising the clamp are positioned for the reception of retaining members 15 and 16, whereby the members comprising the clamp are effec- 85 tively and securely retained upon the edges 7 of the tie 5 and whereby longitudinal or lateral movement of the said members is effectively prevented.

Having thus fully described the invention, what I claim as new is:—

1. In a device of the character described, a tie, said tie being provided with a centrally arranged longitudinally extending projecting portion, the longitudinal edges of 95 the said projection being undercut and converging toward the longitudinal center of the tie, clamping members for the ends of the tie, said clamping members comprising a plurality of elements, each of said elements 100 having its base member provided with an angular cut away portion adapted to engage with the undercut edges of the projection of the tie, the elements being arranged in pairs adjacent each other, and means for securing 105 the members together both longitudinally and transversely.

2. In a device for the purpose set forth, a metal tie, said tie comprising a substantially rectangular member having a central longi- 110

tudinally projecting portion, the edges of the said projecting portions being undercut and converging toward the longitudinal center of the tie, clamping members for the ends, 5 said clamping members comprising four elements, each of said elements having a base portion provided with an offset inclined portion adapted to engage with the undercut projection of the tie, each of the clamping members being further provided with an 10 overlying lip and a horizontally straight

portion positioned directly below the lip, the members being further provided with longitudinal and transverse openings, and removable securing elements for the openings. 15

In testimony whereof I affix my signature in presence of two witnesses.

JOHN S. BUTCHER.
